FIG. 1.

FIG. 2

CHARLES K. RICE

FIG. 3

834

Owen H. Spencer
attorney

UNITED STATES PATENT OFFICE

CHARLES K. RICE, OF INDIANAPOLIS, INDIANA

PANEL RETAINING MEANS

Application filed August 18, 1930. Serial No. 476,175.

This invention relates to means of inserting and retaining panels in lamp shades or the like and one feature of the invention is the provision of a frame structure having openings therethrough and having pocket like channels at the upper and lower extremities thereof.

A further feature of the invention is the provision of means for removably securing a plate like structure in said channels and over said openings.

A further feature of the invention is in so constructing and arranging the frame structure that one or a plurality of objects may be displayed simultaneously from a single or a multiplicity of light structures.

A further feature of the invention is in so constructing and arranging the frame structures that they will form parts of a lamp shade and at the same time exhibit objects carried in the frames.

Other objects and advantages will be hereinafter more fully set forth and pointed out in the accompanying specification.

In the accompanying drawings which are made a part of this application,

Figure 1 is a side elevation of a lamp shade with the frame members incorporated therewith.

Figure 2 is an enlarged detail sectional view through the lamp shade and frame structures attached thereto.

Figure 3 is a horizontal sectional view as seen along line 3—3 of Fig. 2.

Figure 4 is a perspective view of one of the panels adapted to be entered in the frame structure.

Referring to the drawings, the numeral 1 designates a lamp shade, preferably consisting of a frame 2 having section 3 of glass or other material incorporated therewith, said frame being preferably constructed of sheet metal, although it will be understood that other suitable material may be used.

Depending from the edges of the frame 2 are frame forming structures 4, which are likewise preferably formed of metal, said frame forming structures having any suitable number of openings 5 therethrough, for exposing characters or pictures of any suit-

able nature incorporated on panel plates 6.

In order to removably mount the panel plates 6 in position to expose the characters thereon through the openings 5, channels 7 and 8 are located adjacent the upper and lower extremities of the openings 5 and in the rear thereof, the upper channel 7 being of such a depth that the top edge of the panel plate 6 may be elevated therein a sufficient distance to permit the lower edge of the panel plate to pass over the edge of the lower channel 8 with the top edge of the panel plate still remaining in engagement with the upper channel 7 when the lower edge of the panel plate has been lowered into the channel 8.

In order to securely retain the panel plates 6 within the channels 7 and 8 and at the same time prevent rattling of the panel plates, incident to jars or otherwise, spring tongues 9 are attached at one end to one side face of one of the channels, preferably the channel 7 with the free end thereof so curved that the panel plate may be readily entered and forced between the curved ends of the spring tongues and the faces of the frame forming structures 4, the springs preferably engaging the bindings 10 around the panel plates 6, so as not to injure the plates by scratching or otherwise marring the same.

Each opening 5 is separated from the other by means of partition walls 11, thus providing an individual compartment for each panel plate 6, so that the characters on the various plates will be set out individually and it will be understood that each plate may have a subject different from the other.

The frames 2 and 4 are preferably stamped from sheet metal and formed into proper shape, hence can be very cheaply produced at the same time providing a strong and durable structure.

It will likewise be seen that by mounting the panel plates with the frame structure as shown, said panels may be readily removed or inserted into the frames, so that many different plates, having different subject matters thereon, may be placed into the frames during an evening for exhibiting the con-

tents of the plates when the interior of the lamp shade is illuminated.

It will thus be seen that quite an extended entertainment may be given during an evening by having a varied assortment of plates prepared embodying various subjects.

While the description and drawings illustrate in a general way certain instrumentalities which may be employed in carrying the invention into effect, it is evident that many modifications may be made in the various details without departing from the scope of the appended claims, it being understood that the invention is not restricted to the particular examples herein described.

What I claim is:

1. A substantially pyramidal shaped frame arranged for retaining sections of glass or the like, for forming the top of a lamp shade, 20 frame forming structures depending from the lower edges of said first frame and resting in a vertical plane and forming a substantially square contour, said latter frames having a plurality of individual openings for receiving panel forming plates, channels at the upper and lower edges of said openings and integral therewith, the upper channel being greater in depth than the lower one, integral partition walls separating said openings, and 30 springs for holding objects in fixed position within said openings.

2. A substantially pyramidal shaped frame forming the top portion of a lamp shade and having sections of glass or the like incorporating therewith, integral sections depending from the edges of said top forming frame and integral with the frame and describing substantially a hollow square in general outline, said integral sections having object receiving openings therethrough, the lower edges of said depending sections having inwardly and upwardly extending portions forming object receiving channels, and channel forming sections attached to the depending portions above said object receiving openings.

In testimony whereof, I have hereunto set my hand on this the 4th day of August, 1930.
